US0D1026596S

(12) **United States Design Patent** (10) **Patent No.:** **US D1,026,596 S**
(45) **Date of Patent:** **** May 14, 2024**

(54) **SAW CHAIN**

(71) Applicant: **Zhuji Bolin Tools Co., Ltd.**, Zhuji (CN)

(72) Inventor: **Yabo Zhang**, Zhuji (CN)

(**) Term: **15 Years**

(21) Appl. No.: **29/840,975**

(22) Filed: **Jun. 2, 2022**

(51) **LOC (14) Cl. 08-03**

(52) **U.S. Cl.**

USPC **D8/65**

(58) **Field of Classification Search**

(57) **CLAIM**

The ornamental design for a saw chain, as shown and described.

DESCRIPTION

FIG. 1 is a perspective view of a saw chain showing my new design;

FIG. 2 is another perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof; and,

FIG. 8 is a bottom plan view thereof.

The broken lines in the figures depict portions of the saw chain, that form no part of the claimed design.

1 Claim, 5 Drawing Sheets
